UNITED STATES PATENT OFFICE.

THOMAS W. NEELY, OF MARSHALL, ILLINOIS.

PROCESS OF GENERATING STEAM.

SPECIFICATION forming part of Letters Patent No. 758,095, dated April 26, 1904.

Application filed May 2, 1901. Serial No. 58,505. (No specimens.)

To all whom it may concern:

Be it known that I, THOMAS W. NEELY, of Marshall, in the county of Clark and State of Illinois, have invented a new and useful Improvement in Processes of Generating Steam, of which the following is a specification.

My invention is in the nature of a novel process of generating steam in which the heat for converting the water into steam is supplied internally in relation to the shell of the boiler by an electric arc or two electrodes juxtaposed in the relation of an electric arc and immersed in the water and introducing at one of the electrodes hydrocarbon vapor or other combustible gas adapted to unite with the oxygen which may be set free by electrolysis of the water and be burned and by the intense heat of the electric-arc or hydrocarbon flame to form an auxiliary or supplementary source of heat and pressure within the boiler.

In the drawing, the figure is a vertical section of the boiler and a side elevation of the dynamo or electric generator with automatic regulating devices and showing also means for introducing the combustible vapors or gas, the same being one form of mechanical means for carrying out my process.

In the drawing, B is a boiler-shell inclosed on all sides, top, and bottom by a heat-insulating covering B'. The boiler is equipped with the usual feed-water pipe f, manhole m, blow-off pipe b', water-level glass w, steam-gage g, and has within it braces or stay-rods b to enable it to stand a great pressure without bulging at the ends.

D is a dynamo or electric generator whose main conducting-wires M M' lead, respectively, the one to the bottom and the other to the top of the boiler. The wire M' connects with an adjustable carbon electrode C, suspended within the boiler from the top, and the wire M connects with the lower carbon C'. The upper carbon is sustained upon an adjustable rod E', which passes through an insulated stuffing-box x in the top of the boiler and is raised and lowered by a screw-thread meshing with a stationary nut e and an insulated hand-wheel E. The lower car-

bon C' is held upon a hollow rod F, which passes through an insulated bushing y in the bottom of the boiler. The rods E' and F are connected to the carbons or to the carbon-sockets by screw-joints. The lower carbon C' has a central hole H through it, which is in open communication with the bore of the hollow rod F, and an external pipe V, which leads to a source of combustible vapor or gas hereinafter described. When the electric current from the dynamo is taken through the wires M M' to the two carbons and the latter are separated, an electric arc will be established between them even though immersed in the water, and the intense heat will rapidly generate steam and without loss of heat and will under certain conditions also effect the partial decomposition of the water into the constituent gases—oxygen and hydrogen. I take advantage of this to combine in the boiler the nascent oxygen with combustible vapors introduced through the pipe V and the opening in the lower carbon, so as to get a further increase of heat and pressure. The pipe V leads to a carburetor or source of combustible vapors or gas and has a valve t in its length controlled by an arm a', which is normally held at right angles to the pipe by a spring r. The end of the arm a' is connected to a curved armature-core a, that slides in and out the central chamber of a curved helix S', forming a solenoid. The terminals of the helix S' connect with wires 3 4, and these through switch s form a shunt-circuit from the main dynamo-wires M M'. When the shunt-circuit is established through switch s and wires 3 4, the solenoid-armature a pulls up arm a' and opening valve t allows combustible gas to pass through pipe V to the end of the lower electrode, to be there burned. When the dynamo-current is cut off from the boiler by the main switch S or by other means either accidental or otherwise, then spring r pulls the arm a' to its right-angular position, as shown, and closes valve t, cutting off the supply of combustible gas, thus guarding against an over-supply of gas to the boiler and consequent explosion.

To automatically regulate the steam-pres-

sure, a safety-valve *O* has its weighted and spring-held lever *L* organized as a switch and bears a rubbing contact that passes over the graduated face-plates of a rheostat *R*. This 5 rheostat by wires 1 2 is in the field-circuit of the dynamo, and when an excessive pressure in the boiler lifts the safety-valve lever its rubbing contact cuts in a larger resistance of the rheostat, and by reducing the energy of the 10 field-magnets of the dynamo and its electrical generation reduces the activity of steam generation and electrolysis.

Z is a perforated and arched diaphragm placed over the space occupied by the water 15 to prevent the frothing or heaving of the water in case of rapid evaporation, which would make it difficult to determine the water-level.

In this generator the heat is applied to the water or other expansive element direct with- 20 out the intervention of iron or other material that will retard the transmission of heat to the water or other expansive element itself. In the usual types of boilers or generators the heat is 25 really insulated from the water by the relatively poor conductivity of the iron. In other words, the makers of other types of boilers or generators apply their heat on the outside, endeavoring to transmit it to the water within and then try to retain the heat in the boiler.

30 In this boiler or generator the heat is applied within the boiler and is easily retained, as there are no doors to be continually opened, or fronts, or stacks, or walls to radiate or conduct the heat from it, as in ordinary types of 35 boilers. In my generator advantage is taken of the intense heat of the electric-arc and hydrocarbon flame or other forms of intensified heat, and the construction and operation are such as to permit of the almost complete insulation of the heat of the boiler and its 40 contents from the surrounding atmosphere or from other bodies, thus delivering approximately all the energy in the fuel used to the engine or other appliance in the form of dry 45 steam or other vapor. Furthermore, the heat being applied or generated internally permits of the use of boiler-plate of any desired thickness or strength without interfering with the transmission of heat or impairing the efficiency 50 of the boiler, thus rendering it possible to use higher pressure apparatus than heretofore.

In my generator there is no need of flues or tubes on account of the rapid transmission of 55 heat by convection and rapid circulation of heated gases through the water or other expansive element, and the heat all being retained in the generator, except as it passes away to the engine by means of the steam or other expansive element. Thus the generator 60 is rendered much more simple than existing types and allowing freer access to all its internal parts.

Operation: On boiler or generator being started for the first time, or after being opened 65 for any cause, water should be pumped into it

until it reaches the water-line shown in drawing, or nearly so. The electric current is then turned into the boiler, forming a circuit through upper and lower carbons, which should at the time be in contact with each other. Upon 70 raising the upper or positive carbon by means of the adjusting-wheel the arc is established in the water between the carbons. The switch in the circuit leading to the solenoid may then be adjusted to throw it in circuit, whereupon 75 the armature will be drawn up into the solenoid, thus opening the vapor-pipe which supplies the vapor from the carburetor or compressor or other source of combustible gas to the arc through the lower carbon. The water 80 coming in contact with the arc (and by electrolysis) is separated into its elements, the hydrogen being set free and the oxygen forming compounds with the carbon in the hydrocarbon vapor and with the carbon of the pencils between which the arc is formed, thus generating great heat. When the temperature and pressure rise until the desired pressure is reached, the piston in safety-valve begins to rise, thus raising the regulating-arm 85 and cutting in resistance into the fields of the dynamo as the pressure reaches the point for which it is adjusted and does the reverse as the pressure begins to fall. Where the boiler or generator is used regularly every twenty- 90 four or forty-eight hours, there is no need to wait to raise steam, as owing to the high insulation of heat which may be secured one may shut down for a period of from twenty-four to thirty-six hours with but a small loss 95 in pressure or temperature, and the heat being applied to the water as soon as you start to draw on the reserve force of the boiler the normal condition is soon reestablished. In places where no power can be obtained from 100 another source a storage battery or small auxiliary boiler should be installed to be used to supply current when starting boiler anew or after having been opened for any cause.

In will be seen that my invention includes 110 the process of utilizing the expansion of combustible vapors along with steam, but without the incidental objections of the gas or gasoline explosive-engine.

In the gasoline or gas engine as now made 115 the vapor is exploded or suddenly expanded within the cylinder of the engine, thus causing great heat losses in heating the cylinder and in exhaust-gases and from the blow given the piston by the explosion rendering the engine less efficient than were a regular and even expansive force exerted against the piston. My idea is by means of this compressor or generator to expand or explode the gasoline or vapor within my generator, thus compressing the gas and other vapor formed by such expansion and making such a number of small explosions or expansions as to cause an even and regular pressure at the point of delivery to the engine from the generator. Thus the 120 125 130

destructive force or blow delivered to the piston in the gas-engine as it is run to-day would be done away with, and the heat now lost in the cylinder and exhaust-gases of the gas-engine would be transmitted to the water in the generator, thus saving all this loss, as the heat generated would cause an expansion of the water into vapor, thus utilizing approximately the entire number of heat units in the 5 gasoline or other liquid used and delivering an expansive vapor to the engine at a not much higher temperature than that of steam as it is to-day used.

That this generator can be used as readily 15 in domestic heating of houses and in heating other buildings and places of business is self-evident, as owing to the great saving of fuel in this device over others used at present such places could be provided with generators of 20 this type and the necessary current supplied as is the current for illuminating purposes to-day.

I do not claim in this case the mechanical 25 apparatus for carrying out my process, as this has been made the subject-matter of a separate application for a patent filed April 23, 1901, Serial No. 57,131.

Having thus described my invention, what 30 I claim as new, and desire to secure by Letters Patent, is—

1. The process of generating steam and supplementing its expansive power, which consists in passing an electrical current through electrodes immersed in water to form an electric 35 arc with electrolysis of the water, admitting a combustible gas to the said electrodes to be combined with the water-gases by combustion and confining the resultant gaseous

product to form pressure for motive power substantially as described.

2. The process of generating steam and supplementing its expansive power by an internal combustion of gases which consists in decomposing by an electric arc the water of a boiler into its constituent gases, retaining the 45 same under pressure, introducing a combustible gas to the said separated water-gases for union therewith by combustion while still immersed in the surrounding water and controlling the feed of the combustible gas to 50 said electrodes in an automatic way substantially as and for the purpose described.

3. The process of generating steam, and supplementing its expansive power, which consists in decomposing the water by electrolysis 55 and burning an extraneous gas by combination with the disengaged constituent gases of the water, to produce heat and an expansion of the resultant vapors and gases and retaining such gases with the steam for motive 60 power substantially as described.

4. The process of generating steam and supplementing its expansive power, which consists in establishing in the water of a boiler an electrical arc, introducing a combustible 65 gas thereto, regulating automatically the electrical current to the arc, and regulating automatically the admission of the combustible gas to the electric arc and retaining the steam and produced gases under pressure for motive 70 power substantially as and for the purpose described.
